CLAIM

The ornamental design for a rocket-shaped toy, as shown and described.

DESCRIPTION

FIG. 1 is a perspective view of a first embodiment of a design for a rocket-shaped toy;

FIG. 2 is a rear view of FIG. 1; and,

FIG. 3 is a perspective view of an alternative embodiment of the design; the rear view being the same as the first embodiment.

The drawings are lined for color in accordance with MPEP §608.02.
